Patented Apr. 3, 1917.

UNITED STATES PATENT OFFICE.

DOCTOR FRANKLIN OLIVER, OF OAKLAND, CALIFORNIA.

DOOR-BUFFER.

1,221,580.

Specification of Letters Patent.

Patented Apr. 3, 1917.

Application filed July 19, 1911, Serial No. 639,412.

Renewed September 27, 1916. Serial No. 122,579.

To all whom it may concern:

Be it known that I, DOCTOR FRANKLIN OLIVER, a citizen of the United States, and a resident of Oakland, in the county of Alameda and State of California, have invented 5 a new and Improved Door-Buffer, of which the following is a full, clear, and exact description.

The object of the invention is to provide a 10 new and improved door buffer, arranged to offer a light resistance to the door on closing the latter gently, and to offer a heavy resistance on slamming the door, thus preventing injury to the door and door casing, 15 and reducing the shock incident to the slamming of the door to a minimum.

For the purpose mentioned use is made of 20 a light resistance device, actuated on closing the door, a heavy resistance device, and a connecting member moving bodily with the 25 said light resistance device and normally out of engagement with the said heavy resistance device, the said connecting member moving into engagement with the said heavy 30 resistance device on forcibly actuating the light resistance device when slamming the door.

A practical embodiment of the invention 35 is represented in the accompanying drawings forming a part of this specification, in which similar characters of reference indicate corresponding parts in all the views.

Figure 1 is a perspective view of the door 40 buffer in position on the free end of a door; Fig. 2 is a side elevation of the door buffer in position on the door, the latter being shown in section;

Fig. 3 is a sectional side elevation of the 45 same; and Fig. 4 is a sectional plan view of the same as applied and showing the door at the point of closing.

The door buffer is mounted on a suitably 50 constructed frame or casing A mortised in the free end of the member B and secured to the latter by screws or other suitable means. On the buffer casing A is mounted to slide a latch bolt C having a beveled head C' adapted to engage a plate D attached to 55 the casing E, so that when the door is closed the beveled head C' engages the plate D to push the latch bolt C inward against the tension of a light resistance spring F arranged in the casing A and pressing the latch bolt C in a forward direction with a

view to normally hold the head C' projected beyond the free end of the door, as plainly indicated in the drawings. The outward movement of the latch bolt C is limited by a stop pin C² carried by the bolt and 60 adapted to abut against the front end of the buffer casing A (see Figs. 2 and 4).

The latch bolt C is provided within the casing A with an opening C³ in which extends a connecting member G provided on its top with teeth G' adapted to interlock with teeth H' formed on a slide H mounted to slide on a bolt I held in the casing A and arranged parallel to the latch bolt C. The slide H is pressed on by one end of a spring J coiled on the bolt I and abutting against the nut I' of the bolt I, and which nut serves to adjust the tension of the spring J. The spring J is considerably heavier than the spring F and it forms with the slide H a 70 heavy resistance device in comparison with the light resistance device formed by the latch bolt C and its spring F. The slide H is held against turning on the bolt I by a lug or a pin K attached to the slide H and engaging an elongated guideway A' formed on the buffer casing A.

The forward wall C⁴ of the opening C³ in the latch bolt C is made V-shaped, and on it fits a V-shaped notch G² formed on the forward end of the connecting member G, which latter is also provided with an inclined slot G³ through which extends a pin C⁵ forming part of the latch bolt C. It will be noted that the inclined walls of the slot of the bolt meet at the center of the bolt, while the inclined walls of the notch of the connecting member meet at one side of the center of said member; consequently when the latch bolt is pushed forcibly and suddenly 90 inward, the upper inclined wall thereof engaging the upper and longer inclined wall of said member will with the pin C⁵ working in the inclined slot G³ of the member, cause the said member to be forced upwardly 100 to the position shown in Fig. 3. Normally the connecting member G is in its lowermost position as indicated in Fig. 2, so that the teeth G' are free of the teeth H', and consequently when the door B is gently closed 105 and the latch bolt C is moved inwardly against the tension of its light spring F then the connecting member G simply moves with the latch bolt C without changing its position. When, however, the door B is 110

slammed or forcibly closed then the forcible blow given to the latch bolt C causes an upward movement of the connecting member G whereby the teeth G' move into engagement with the teeth H' of the slide H, as shown in Fig. 3, and the latter is now brought into action, that is, the slide H is moved inwardly with the connecting member G and the latch bolt C, whereby the 10 spring J is compressed, that is, a heavy resistance is offered to the door when slamming the same. As soon as the force in slamming the door is expended against the heavy resistance device, the spring J returns the slide 15 H to normal position and the connecting member G is now free to drop by gravity and thus return to normal position, that is, out of engagement with the slide H.

From the foregoing it will be seen that 20 the latch bolt C offers a light resistance to the door on gently closing the same, but when the door is slammed the heavy resistance device is automatically brought into action so as to take up the shock incident to 25 slamming the door, thereby preventing injury to the door casing and the wall in which the door casing is located. By arranging the guideway for the connecting member G in the latch bolt C in the manner 30 described and shown in Fig. 3, it is evident that when the connecting member G is actuated on slamming the door, it not only moves upward but also lengthwise and in a reverse direction, to that in which the latch 35 bolt C is moving at the time, to cause a firm interlocking with the slide H as soon as possible to bring the heavy resistance device into action.

The door buffer shown and described is 40 very simple and durable in construction, and is composed of comparatively few parts, not liable easily to get out of order.

I do not claim broadly in this application a light resistance device actuated on closing 45 the door with ordinary force and a heavy resistance device controlled by the light resistance device and operated thereby upon the door slamming, the same being claimed in the companion application No. 637,278.

50 Having thus described my invention, I claim as new and desire to secure by Letters Patent:

1. A door buffer, comprising a latch bolt, a light resistance device for the bolt, a 55 heavy resistance device, and a connecting member moving bodily with the said light resistance device and normally out of engagement with the said heavy resistance device, the said connecting member moving 60 into engagement with the said heavy resistance device on forcibly actuating the light resistance device when slamming the door.

2. A door buffer, comprising a latch bolt, 65 resistance devices, one acting on the bolt and provided with a light spring and the other

adjacent the bolt and provided with a heavy spring, and a connecting member carried by the said light spring resistance device and out of engagement with the said heavy spring resistance device on gently closing 70 the door, the said connecting member moving into engagement with the said heavy spring resistance device on forcibly actuating the said light spring resistance device when slamming the door. 75

3. A door buffer, comprising a latch bolt, a light spring pressing the same, a heavy spring resistance device adjacent the said latch bolt, and a connecting member carried by the said latch bolt and normally inactive 80 on gently closing the door, the said connecting member being movable on the latch bolt and adapted to engage the said heavy spring resistance on forcibly actuating the said latch bolt when slamming the door. 85

4. A door buffer, comprising a latch bolt, a light spring pressing the said bolt to hold it in projected position, a connecting member mounted to slide lengthwise and upward on the latch bolt, and a heavy resistance device adjacent the said latch bolt and adapted to be engaged by the said connecting member on forcibly actuating the latch bolt when slamming the door. 90

5. A door buffer, comprising a latch bolt, 95 a light spring pressing the said bolt to hold it in projected position, a connecting member mounted to slide lengthwise and upward on the latch bolt, a slide adjacent to the said latch bolt and adapted to be engaged by the 100 said connecting member, and a heavy spring pressing the said slide.

6. A door buffer, comprising a latch bolt, a light spring pressing the said bolt to hold it in projected position, a connecting member mounted to slide lengthwise and upward on the latch bolt and provided with teeth at the outer face, a slide adjacent the said latch bolt and provided with teeth adapted to be engaged by the teeth of the said slide, and a 105 heavy spring pressing the said slide. 110

7. A door buffer, comprising a casing, a latch bolt mounted to slide on the said casing and provided with guideways, a light spring pressing the said latch bolt, a connecting member mounted to slide on the said latch bolt and provided with teeth, a resistance slide mounted in the said casing and provided with teeth adapted to be engaged by the teeth on the said connecting member, 115 120 and a heavy spring pressing the said slide.

8. A door buffer, comprising two sliding members having unequal resistance, one of the members being adapted to project from a door, and the members being normally out 125 of engagement, and means for connecting the said members when the projecting one is suddenly and forcibly pushed inward.

9. In a door buffer, the combination with a spring actuated latch bolt, of a resistance 130

device operated by the spring actuated latch bolt when the latter is suddenly and forcibly pushed inward.

10. In a door buffer, the combination with 5 a sliding and spring actuated latch bolt, of a resistance device and means for connecting the bolt with the resistance device, when the bolt is suddenly forcibly pushed inward.

11. In a door buffer, the combination of 10 a sliding latch bolt, and a resistance device

with which the bolt is engageable when the latter is suddenly and forcibly pressed inward.

In testimony whereof I have signed my name to this specification in the presence of 15 two subscribing witnesses.

DOCTOR FRANKLIN OLIVER.
